UNITED STATES PATENT OFFICE.

ZACHARY T. HALL, OF PHILADELPHIA, PENNSYLVANIA.

DESIGN FOR A FLUE STOPPER AND COLLAR.

SPECIFICATION forming part of Design No. 18,059, dated February 14, 1888.

Application filed December 31, 1887. Serial No. 259,530. Term of patent 7 years.

To all whom it may concern:

Be it known that I, ZACHARY T. HALL, a citizen of the United States, residing in the city and county of Philadelphia, State of Pennsylvania, have invented and produced a new and original Design for a Flue Stopper and Collar, of which the following is a specification, reference being had to the accompanying photograph, forming part thereof.

The leading feature of my design for a flue stopper or collar is the body having thereon a circular row of crescents and marginal beads.

In the drawing, A represents the body of a

flue stopper or collar, having on its breast a center field, A', inner circular bead, b, a circular row, a, of crescents, and an outer bead, b'.

I claim—

A design for a flue stopper or collar, consisting of a body having a circular row of crescents with marginal beadings, substantially as shown and described.

ZACHARY T. HALL.
